UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

THREAD-LAYING MECHANISM FOR SEWING MACHINES.

1,411,891.

Specification of Letters Patent.

Patented Apr. 4, 1922.

Application filed March 10, 1916. Serial No. 83,300.

To all whom it may concern:

Be it known that I, DUDLEY S. SEYMOUR, a citizen of the United States, residing at Oak Park, in the county of Cook, State of Illinois, have invented certain new and useful Improvements in Thread-Laying Mechanism for Sewing Machines, of which the following is a description, reference being had to the accompanying drawing and to the figures of reference marked thereon.

The invention relates to new and useful improvements in sewing machines, and more particularly to the thread laying mechanism which lays the thread back and forth in front of the needle or needles so that said thread is secured to the upper face of the fabric by the stitching threads.

An object of the invention is to provide a thread laying mechanism wherein the supporting arm for the thread engaging device is located beneath the supporting head for the needle bar and is mounted on an oscillating support extending into the head so that the train of mechanism for operating the support for the arm carrying the thread engaging member may be completely housed within the needle head.

A further object of the invention is to provide an operating mechanism of the above character for the thread engaging member wherein the oscillating support for the arm which carries the thread engaging member is actuated from the shaft which reciprocates the needle bar.

These and other objects will in part be obvious and will in part be hereinafter more fully disclosed.

In the drawings, which show by way of illustration, one embodiment of the invention:

Figure 1 is a view, partly in section and partly in side elevation, showing a portion of a sewing machine having the improvements applied thereto;

Fig. 2 is a vertical sectional view through the forward end of the overhanging arm and the supporting head carried thereby;

Fig. 3 is a view, partly in section and partly in plan, showing the presser foot, the presser bar, the thread laying devices and the trimming blades;

Fig. 4 is a detail in front elevation showing the needles and the thread laying devices;

Fig. 5 is a horizontal sectional view

through the lower end of the head and above the lower supporting bearing for the presser bar;

Fig. 6 is a sectional view on the line 6—6 of Fig. 1;

Fig. 7 is a sectional view on the line 7—7 of Fig. 1;

Fig. 8 is a sectional view on the line 8—8 of Fig. 7;

Fig. 9 is a detail, partly in section, showing the presser bar, the supporting shaft for the movable trimming blade, and the connecting arm which holds the presser bar from oscillating, and a portion of the tension spring which operates upon the presser bar;

Fig. 10, is a diagrammatic view on an enlarged scale showing two fabric sections, the threads joining the same on the upper face, the needles, the fixed thread guide, and the cooperating hooks, said hooks being out of engagement with the cross threads; and

Fig. 11 is a similar view, but showing the hooks moved forward and the cross threads formed into loops to receive the respective needles.

The improved thread laying mechanism is shown as applied to a sewing machine consisting of a work support 1, which is preferably in the form of a cylindrical work supporting arm. Said sewing machine also has an overhanging arm carrying a supporting head 2 at its outer end. This supporting head is formed with a chamber which is closed by a cover plate 2^a, thus forming an enclosed supporting head at the free end of the arm. Reciprocating in said supporting head is a needle bar 3 which, as herein shown, carries a pair of needles 4 and a pair of needles 5. Cooperating with the pair of needles 4—4 beneath the work support is a looper 6, and cooperating with the needles 5—5 beneath the work support is a looper 7. Mounted in suitable bearings in the overhanging arm is a shaft 8 which projects into the supporting head 2. Said shaft is provided with an arm 9 which is connected by a link 10 to a collar 11 fixed to the needle bar so that, as the shaft 8 oscillates, the needle bar 3 will be reciprocated.

The material is held on the work support 1 by a presser foot 12. Said presser foot is carried by a presser bar 13 which is mounted in suitable bearings formed in the supporting head 2. In rear of the presser bar 13

90

95

100

105

110

is a vertical shaft 14 which is mounted in bearings 15 and 16 projecting rearwardly from the supporting head 2. This shaft 14 is provided with an arm 17 at its lower end, 5 and the arm 17 carries a trimmer blade 18. This trimmer blade 18 moves in a horizontal plane and cooperates with a fixed blade 19 which is clamped to the presser foot. The presser foot 12 is formed with a slot 20 10 which receives the upturned edges of the two fabric sections to be joined and the trimming device trims off these edges, after which they are abutted. The presser foot is provided with a needle slot 21 which receives the needles 4—4, and said presser foot 15 has a stitch tongue 22 which projects into said slot between the needles. The presser foot also has a second needle slot 23 for the needles 5—5 and a stitch tongue 24 which 20 projects between this pair of needles.

Cooperating with the rear pair of needles 4—4 is a thread hook 25, and cooperating with the front pair of needles is a thread hook 26. These thread hooks are formed 25 with notches 27 in their outer ends. The thread hooks are clamped to an arm 28 which is fixed to a sleeve 29 by a clamping screw 30.

In Figs. 10 and 11 I have shown diagrammatically two fabric sections A and B 30 which are connected by the stitching mechanism including my improved thread laying devices. The edges of these fabric sections are abutted at C. The needles 4—4 are 35 preferably so positioned that the left hand needle is nearer the meeting edges of the fabric sections than the right hand needle, while the pair of needles 5—5 is positioned so that the right hand needle is nearer the 40 meeting edges of the fabric sections. The needles 4—4 carry threads *a—a*, while the needles 5—5 carry threads *b—b*. The thread hook 25 operates upon a cross thread *c*, while the thread hook 26 operates upon a cross 45 thread *d*. The cross threads *c* and *d* are led respectively through guide eyes 32 and 33 which are formed in an arm 34 fixed to the supporting head 2. This thread guiding arm 34 has no movement but is fixed relative 50 to the needles so as to cooperate with the thread hooks in properly positioning the cross threads for engagement with the needle threads.

In Fig. 10 the thread hooks are at the 55 rear end of their stroke, and their hook ends 27 are adjacent the thread guiding eyes 32 and 33 respectively. As the hooks move forward they will engage their respective cross threads and carry the same to the 60 position indicated in Fig. 11. The strand of cross thread running from the notched end of the thread hook to the supply passes between the needles of the respective pair with which it cooperates, while the strand 65 of the cross thread running from the hook

to the fabric passes in rear of both needles. The result is that a loop is formed in the cross thread for the left hand needle, while the cross thread is carried around the right hand needle by the feed of the fabric and 70 the next following stroke of the thread hook. This lays the cross thread back and forth and around each needle puncture. The cross thread *c* overlies the cross thread *d* and the needle threads *b* at the right of the seam 75 and both cross threads extend across the meeting edges of the fabric. It is understood that the needle loops of each respective pair of needles are connected beneath the material by a looper thread so that the 80 meeting edges are crossed by the looper thread beneath the material. This seam forms no part of my present invention, but has been described in detail in order that the operation of the thread laying devices 85 may be better understood.

The sleeve 29 surrounds the presser bar 13 and is mounted in the lower bearing 35 for said presser bar. The sleeve is formed with a shoulder 36 which rests on the upper 90 face of the bearing and the arm 28 is provided with a collar clamped to the lower end of this sleeve by the set-screw 30, as above noted. This collar prevents the sleeve 29 from moving upwardly.

The shaft 8 is provided with a second arm 37 which is connected to a rock lever 38 by a link 39. This rock lever is mounted on cone bearings 40 and 41 which are carried by a supporting stud 42. The bearing 41 is preferably integral with the stud, while the cone bearing 40 is adjustable thereon and is held in place by a nut 43. The stud 42 extends through a lug 44 formed integral with the overhanging arm and is clamped 100 in position by a nut 45. The rock lever 38 has an upwardly extending arm 46 to which the link 39 is pivoted, and also a downwardly extending arm 47. A link 48 is connected at one end to a ball stud 49 carried 105 by this arm 47, while the other end of the link 48 is connected to a ball stud 50 on an arm 51 formed integral with the sleeve 29. As the needle shaft 8 oscillates, it will not only reciprocate the needle bar through the 110 oscillation of the arm 9, but through the oscillation of the arm 37 and the rock lever 38, the sleeve 29 will also be oscillated, and this will in turn oscillate the thread hooks 115 25 and 26.

Fixed to the upper end of the sleeve 29 is an eccentric 52. An eccentric strap 53 cooperates with said eccentric, and said strap is connected to a ball stud 54 carried by an arm 55 attached to the shaft 14. The oscillation of the sleeve 29 will, therefore, oscillate the shaft 14, and this in turn will oscillate the trimmer blade 18. The shaft 14 is moved endwise by a spring 56 which bears at its lower end against the arm 17 and at 120 125 130 135 140

its upper end against a washer 57 seated in a recess 58 at the lower face of the bearing 15. The presser bar 13 is provided with an arm 59 which projects rearwardly, and 5 the shaft 14 freely extends through this bar. This prevents the presser bar from oscillating through the strain of the cutting action.

Said arm 59 has an annular recess in its upper face adapted to receive an inverted 10 cup 60. A spring 61 surrounding the shaft 14 rests upon the upper face of the cup 60, and the upper end of this spring bears upon the threaded sleeve 62 which is threaded in the upper bearing 16, and the threaded 15 sleeve becomes the bearing sleeve for the shaft 14 which may not only oscillate in said bearing sleeve but may be freely moved endwise therein. The purpose of this spring 61 is to yieldingly force the presser bar 20 downwardly and hold the presser foot on the work support.

From the above description, it will be apparent that I have provided a thread laying mechanism wherein the thread hooks are 25 positively operated from the same train of mechanism which reciprocates the needle bar and the operating devices for the thread manipulating members are disposed within the supporting head at the forward end of 30 the overhanging arm. This not only affords an efficient housing for the operating parts, but will provide a direct short train of mechanism which is substantially free from undesirable vibrations in the rapid movements of the parts.

It is obvious that minor changes in the details of construction and the arrangement of parts may be made without departing from the spirit of the invention as set forth 35 in the appended claims.

Having thus described the invention, what is claimed as new is:—

1. A sewing machine including in combination, a work support, an overhanging 40 arm, a supporting head at the free end of 45 said overhanging arm, a needle bar operat-

ing shaft in said overhanging arm projecting into said supporting head, a needle bar mounted in said supporting head, means for reciprocating said needle bar from said 50 shaft, two needles carried by said needle bar, a thread hook cooperating with the needles, a stationary thread guide for said thread hook, a member mounted in said supporting head to oscillate about a vertical 55 axis and carrying said thread hook, a rock lever mounted in said supporting head and oscillating about a horizontal axis, a link connecting said rock lever to said oscillating member, and means for oscillating said 60 rock lever from said needle bar operating shaft.

2. A sewing machine including in combination, a work support, an overhanging arm, a supporting head at the free end of said 65 overhanging arm, a needle bar operating shaft in said overhanging arm projecting into said supporting head, a needle bar mounted in said supporting head, two needles carried by said needle bar, means for reciprocating said needle bar from said shaft, a thread hook cooperating with the needles, a stationary thread guide for said thread hook, a member mounted in said supporting head to oscillate about a vertical axis and 70 carrying said thread hook, a rock lever mounted in said supporting head and oscillating about a horizontal axis, a link connecting said rock lever to said oscillating member, means for oscillating said rock lever from said needle bar operating shaft, a supporting stud carried by the overhanging arm, and cone bearings mounted on said supporting stud on which said rock lever 75 oscillates.

In testimony whereof, I affix my signature 80 in the presence of two witnesses.

DUDLEY S. SEYMOUR.
